RIVETED GARMENT

Milton Grunbaum, San Francisco, Calif.

Application July 7, 1934, Serial No. 734,073

3 Claims. (Cl. 2—247)

This invention relates to riveted garments and especially to improvements in the construction and assembling of the fabric forming the garments whereby the rivets become covered and concealed.

In the manufacture of garments, such as overalls and the like, it is common practice to reinforce and strengthen such garments at the points subjected to the greatest strain; for instance, at the corners of the pockets, at the crotch of the pants, and so on, by placing copper rivets at these points.

Overalls are worn by many people and among them cattlemen, farmers, and many outdoor workers. In the case of cattlemen, the projecting rivets often scratch or mar the saddle leather. In the case of farmers and other outdoor workers who use automobiles more than horses, there is a chance that the rivets may scratch the finish of the car, the upholstery, the furniture in the home, and so on, and besides that the rivets are unsightly and do not add but rather detract from the finish and general appearance of the garment.

The object of the present invention is generally to improve the construction and operation of garments of the character described, and especially to so construct and arrange the fabric during the assembling and sewing thereof that the reinforcing rivets will become covered and concealed and thereby improve the appearance of the garment, and more important avoid scratching or marring of the objects with which the garments may contact.

The garment and the method of applying the reinforcing rivets thereto is shown by way of illustration in the accompanying drawings, in which—

Fig. 1 is a plan view of a pocket blank such as used in forming a patch pocket.

Fig. 2 shows the blank hemmed along the top and two side edges and ready for application to the garment.

Fig. 3 shows the manner in which the corners of the pocket patch are riveted to the garment.

Fig. 4 shows a completed patch pocket.

Fig. 5 is an enlarged section taken on line V—V of Fig. 4, showing the manner in which the rivets are covered and concealed.

Fig. 6 shows a portion of a garment having an insert pocket formed therein, this view also showing the position of the reinforcing rivets.

Referring to the drawings in detail, particularly Fig. 4, A indicates the body of the material forming the garment and B a patch pocket attached thereto.

Patch pockets are usually reinforced at the corners, indicated at 2 and 3, by passing rivets through the material forming the patch of the pocket and also through the body material but

as previously stated such rivets project from the fabric or material and as such are liable to scratch and mar objects with which the material comes in contact.

To cover and conceal the rivets the following method of construction and assembly is resorted to. By referring to Fig. 1, which is a plan view of the blank forming the patch or the pocket, it will be noted that the end indicated at 4 will, when the pocket is finished, form the upper edge 10 or entrance to the pocket. This edge is cut at the points indicated at 5 and 6 to a suitable depth so as to permit the material indicated at 7 to be folded upon itself to form a finished hem such as shown at 8 in Fig. 2. The sides of the patch are 15 then folded along the dotted lines indicated at 9—9 and these side folds form the side hems of the patch and they also form two projecting tabs, such as indicated at 10—10. When a blank has been cut, folded, and hemmed, it is placed on the 20 body material A of the garment, as shown in Fig. 3, and the tabs 10—10 are riveted to the body material by rivets 11—11. The pocket or patch is then folded back upon itself so as to cover and conceal the rivets and to lie flat against the body 25 material of the garment, and when so folded will assume the position shown in Fig. 4; the pocket being finally completed by stitching it along the sides and the bottom as indicated by dotted lines at 12, 13 and 14.

Fig. 5 clearly shows the manner in which the rivet is covered and concealed and so does Fig. 4.

The manner of covering and concealing the rivet is not limited to the construction of patch pockets alone. It is equally applicable to other parts of the garment, for instance to an insert type of pocket such as shown in Fig. 6. In this instance the strip of material forming the waistband and indicated at 15 is folded over the rivet indicated in dotted lines at 16, and thus covers 40 one of the rivets. A second rivet indicated in dotted lines at 17 is covered by the section of body material indicated at 18, which is folded over. The opening to the insert pocket is indicated at 19, and the pocket material is indicated 45 by dotted lines at 20.

In forming the crotch of the pants the rivet is placed as indicated by dotted lines at 21, and when so placed, becomes covered with the material.

Suffice it to say that rivets, or other reinforcing means employed, may be placed wherever desired and when placed in the manner described will become covered and concealed with material, thus avoiding scratching or marring of objects 55 with which the garment comes in contact, and furthermore, improving the general appearance of the garment.

While the garment here illustrated has been described as reinforced at several points by means 60

of rivets, staples, other metallic or similar fastening means may be employed and covered and concealed in the same manner, and while the invention has been described in conjunction with 5 overall it is obviously applicable to garments of varying types; and while other features of the invention have been more or less specifically described, I wish it understood that various changes may be resorted to within the scope of the 10 appended claims. Similarly, that the materials and finish of the several parts employed may be such as the manufacturer may decide, or varying conditions or uses may demand.

Having thus described my invention, what I 15 claim and desire to secure by Letters Patent is—

1. A method of riveting a patch pocket to a garment and covering and concealing the rivets, which consists in providing a patch pocket with rivet receiving tabs at opposite sides of its upper 20 edge, positioning the pocket in inverted order in superimposed contacting relation on the garment, affixing rivets through the garment and through 25 said tabs at points adjacent to the ends of the seam to be made and thus securing the pocket to the garment, reversing the order of the said inverted pocket by folding the same adjacent to and over the rivets and thereby covering the 30 rivets, and then seaming the two parts together to permanently hold the pocket in its last mentioned position.

2. A method of reenforcing seams for pockets and for covering and concealing the reinforcement, which consists in cutting the top edge of a pocket blank inwardly at two points spaced 35 from the side edges of the blank, folding over

the portion of the blank intermediate the points at which it is cut and hemming the same thereby providing a reenforced pocket mouth portion and projecting tabs at opposite sides of said reenforced mouth, folding over portions of the remaining side edges of the pocket blank and said tabs into superposed contacting relationship to reinforce the same, positioning the pocket blank thus formed in inverted superimposed contacting relation with respect to the garment to which 10 it is to be seamed, inserting a metallic reenforcing and fastening means through each of the said reenforced tabs and the garment, reversing the order of the inverted pocket blank by folding the same at the inner ends of the tabs over 15 the metallic reenforcing means on the line of the mouth of the pocket thereby covering the metallic fastening means and then seaming the reenforced edges of the pocket blank, exclusive of the mouth portion, to the garment. 20

3. A patch pocket for garments provided with a hem along a portion of its upper edge terminating at the ends of the hem in spaced relation to the opposite side edges of the pocket, said side edges having hems whose upper portions have 25 reverting ends from the line of the said upper hem of the pocket, rivets securing the pocket to a garment, said rivets extending through said reverting ends of the side hems and being covered and concealed by the upper portions of the said 30 side hems, and seams extending along the side and bottom edges of the pocket connecting the same to a garment continuously from one rivet to the other.

MILTON GRUNBAUM. 35
